US0D1026900S

(12) **United States Design Patent** (10) **Patent No.:** **US D1,026,900 S**
(45) **Date of Patent:** **** May 14, 2024**

(54) **WEARABLE DEVICE WITH GRAPHICAL
USER INTERFACE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Marine C. Bataille**, San Francisco, CA (US); **Kevin Will Chen**, Cupertino, CA (US); **Abidur Rahman Chowdhury**, San Francisco, CA (US); **Andrew Patrick Clymer**, San Jose, CA (US); **Clara Geneviève Marine Courtaigne**, Palo Alto, CA (US); **Markus Diebel**, San Francisco, CA (US); **Alexandre B. Girard**, Sunnyvale, CA (US); **Jonathan Gomez Garcia**, San Francisco, CA (US); **Aurelio Guzmán**, San Jose, CA (US); **M. Evans Hankey**, San Francisco, CA (US); **Anne-Marie Heck**, San Francisco, CA (US); **Moises Hernandez Hernandez**, Palo Alto, CA (US); **Richard P. Howarth**, San Francisco, CA (US); **Julian Jaede**, San Francisco, CA (US); **Duncan Robert Kerr**, San Francisco, CA (US); **Kainoa Kwon-Perez**, San Francisco, CA (US); **Nicolas Pedro Lylyk**, Los Gatos, CA (US); **Aaron Mathew Melim**, San Francisco, CA (US); **Peter Russell-Clarke**, San Francisco, CA (US); **Benjamin Andrew Shaffer**, San Jose, CA (US); **Clement Tissandier**, San Francisco, CA (US)

(73) Assignee: **Apple Inc.**, Cupertino, CA (US)

(**) Term: **15 Years**

(21) Appl. No.: **29/864,321**

(22) Filed: **May 20, 2022**

(51) **LOC (14) Cl.** **14-02**

(57) **CLAIM**

The ornamental design for a wearable device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a wearable device with graphical user interface showing the claimed design;

(Continued)

FIG. 2 is a rear perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top plan view thereof; and,
 FIG. 8 is a bottom plan view thereof.
